(57) **CLAIM**

The ornamental design for composite seal member for semiconductor production apparatus, as shown and described.

DESCRIPTION

1.1 is a perspective view of a composite seal member for semiconductor production apparatus, showing our new design;

1.2 is a front elevation view thereof;

1.3 is a rear elevation view thereof;

1.4 is a left side elevation view thereof;

1.5 is a right side elevation view thereof;

1.6 is a top view thereof;

1.7 is a bottom view thereof;

1.8 is a cross-sectional view thereof;

1.9 is an enlarged cross-sectional view of a portion thereof; and

1.10 is an enlarged cross-sectional view of a portion thereof in a condition of use.

The broken lines shown in Reproduction 1.10 are for the purposes of illustrating environmental structure and form no part of the claimed design.
